UNITED STATES PATENT OFFICE.

FRANCIS E. STEVENSON, OF MOUNT GILEAD, OHIO, ASSIGNOR TO THE HYDRAULIC PRESS MANUFACTURING COMPANY, OF MOUNT GILEAD, OHIO.

HYDRAULIC BRICK PRESS.

Application filed August 24, 1923. Serial No. 659,188.

This invention relates to a press for the manufacture of bricks or blocks from a mixture of fibrous material such as cotton stalks and the like with cinders, the whole being held together by a suitable binder, such as asphaltum. These materials are only illustrative and not limiting, since many features of the invention may be used with other materials and for the production of bricks of a different character.

The supply, mixing and feeding tanks together with the means for controlling the feed of material, are similar to those shown in Patent 1,874,373, granted April 12, 1921 to M. P. Andrews. Many details are different, and there is employed a hydraulic press mechanism instead of the mechanical pressing device shown in said patent.

There is provided a reciprocating press plunger driven from sources of high and low pressure. The charging mechanism operates at right angles to the movement of the press plunger and is preferably operated by steam. The charging device has two compartments to cooperate with two openings in the bottom of the filling tank, and its movement is intermittent. The press plunger makes a forward and return stroke for each of the inward and outward movements of the charging device.

The beginning of the movement of the press plunger takes place under low pressure, but the high pressure is admitted at a certain point and completes the pressing of the brick. While these parts return to starting position, the charging device is given a shifting movement.

The pressing tunnel consists of heavy cast iron sections made to lock together without bolts and it is lined with steel plates. The outer end of the tunnel is open and the friction between the walls of the same and the bricks is sufficient to provide the proper resistance to the movement of the bricks and determine the necessary pressure. The walls of this tunnel, as well as those of the charging device, have steam and water pipes therein so that the temperature may be controlled and thereby the resistance to the movement of the bricks through the tunnel. In this manner the amount of pressure applied to the bricks can be varied. Thermostats may be provided as desired to control these pipes and maintain the desired temperatures.

Other objects of the invention will be apparent from the following detailed description and the appended claims.

In the drawings:

Figure 1 is a side elevation of the press.

Figure 2 is an end elevation thereof.

Figure 3 is a top plan view of the hydraulic mechanism and charging device with portions of the press tunnel and charging tunnel in section.

Figure 4 is a side elevation of a portion of the hydraulic control mechanism, with parts in section.

Figure 5 is a view on an enlarged scale of the extreme right hand portion of Figure 4, on the line 5—5 of Figure 3.

Figure 6 is a view of a part of the mechanism shown in Figure 5 looking at right angles to said figure.

Figure 7 is a sectional view through the charging mechanism.

Figure 8 is a view on the line 8—8 of Figure 7.

Figure 9 is a view on the line 9—9 of Figure 3.

Figure 10 is a view on the line 10—10 of Figure 9.

Figure 11 is a view of a detail.

The press is mounted on a base 1 which may be made of concrete or other suitable material and of proper size. The various mixing and supply tanks with their feeding mechanisms are mounted in a frame supported on the base and comprising vertical members 2 and 3, top cross pieces 4 and intermediate cross pieces 5 and 6. Suitable braces 90 may be employed as desired but these have been omitted for clearness of illustration.

A shaft 7 is mounted in bearings 8 carried by the top of the frame and a pulley 9 on said shaft is driven by a belt 10 from any desired source of power. A bevel gear 10' on the inner end of the shaft 7 meshes with a bevel gear 11 on a vertical shaft 12. This shaft has a pinion 13 on its outer end meshing with a gear 14 on a shaft 15 which is provided with a gear 16 meshing with a gear 17 on a shaft 18. The gear 17 also meshes with another pinion 19 on a shaft 20. By means of this mechanism, the various shafts which lead to the supply, mixing and feed tanks are driven.

The machine embodies a fibre tank 21, a cinder tank 22, a mixing tank 23 and a feed-

ing tank 24, all of which are suitably supported from the framework. The fibre storage tank 21 has a steam jacket 25 and the shaft 20 extends into the tank and is provided near the bottom with a single bladed agitator 26. The cinder tank 22 is much smaller than the fibre tank and is also provided with a steam jacket 27. The shaft 18 extends through its center and is provided near the bottom with a single bladed agitator 28.

The mixing tank 23 underlies both the fibre and cinder tanks so that material may be fed from each of these tanks into the mixing tank. It has a steam jacket 29 and the shaft 15 extends through its center. The shaft is provided with mixing arms 30 and the projecting arms 31 attached to the wall of the tank cooperate therewith to produce an effective mixing of the contents. The bottom of this tank is preferably steam heated.

From the mixing tank the material passes to the feeding tank 24 which has a steam jacket 32 and a steam heated bottom. This tank is double and has a center portion 33 in the form of a cylinder which has attached to its top a gear 34 which meshes with a pinion 35 on the shaft 12. Arms 36 project from the outer wall of the cylinder 33 and cooperate with arms 37 projecting inwardly from the wall of the tank. Through the cylinder 33 passes a chute 38 through which are fed wooden plates 39 (see Figure 3) which form separators between the bricks.

The fibre tank is provided with a measuring box 40 and the cinder tank with a proportionally smaller measuring box 41. A link 42 extends from the measuring box 40 and a link 43 from the measuring box 41, both links being attached to a shaft 44 mounted in bearings 45 supported on the cross bars 6 or other suitable portion of the framework. An arm 46 on this shaft is connected by a link 47 to any desired form of ratchet gear measuring mechanism 48 which controls the flow of the hot binder from its container 49. The shaft 44 has a downwardly extending arm 50 which is actuated to rock the shaft as hereinafter set forth.

The feeding tank is provided in its bottom with two openings 51 and 52 beneath which reciprocates a charging device 53 which moves to and fro in a tunnel 54 which is at right angles to the main press tunnel 55. (See Figures 3, 7 and 8.) This charging device has two compartments 56 and 57 so located that when the compartment 56 underlies the opening 51 in the feeding tank, the compartment 57 will be in line with the press tunnel, while when the compartment 57 underlies the opening 52 in the feeding tank the compartment 56 will be in line with the press tunnel. The charging device is

reciprocated from a piston rod 58 which is connected thereto, the movement of this latter being governed as hereinafter set forth. At each end the charging device is provided with a downwardly extending lug 59 provided with an adjustable set screw 60 adapted to contact with the frame in order that the movement of the charging device may be exactly regulated.

The press tunnel is formed of two heavy cast-iron sections 61 and 62 made to interlock without the use of bolts, and liners 63 of steel are employed which may be removed when desired and replaced. The castings of the press tunnel may be provided with steam and water pipes 64 whereby the temperature of the walls of the tunnel may be regulated. The outer end of this press tunnel is open, and the resistance of the movement of the bricks therethrough due to the friction with the sides of the tunnel, determines the amount of pressure given the brick. Obviously the friction varies with the temperature, and thermostats may be provided whereby the temperature can be kept at any desired point. The use of thermostats to govern the flow of water or steam is so common that it has not been illustrated on the drawings. The walls of the charging tunnel may also be provided with steam and water pipes 65.

The piston 58 of the charging device is given movement from a steam cylinder 66 into which steam enters through a pipe 67 passing through a valve chamber 68 the valves of which are controlled by a link 69. Any ordinary or suitable valve mechanism may be employed since it is only necessary that the movement of the link 69 will operate the valve to admit steam to one or the other side of the piston head in the cylinder 66 and thereby afford movement of the piston rod 58 in one or the other direction.

The link 69 is connected to a slidable member 70 to which is adjustably connected one arm 71 of a bell crank pivoted at 73 the other arm 74 of which is provided with a projection 75. Similarly connected to the member 70 is an arm 76 of a second bell crank pivoted at 77 whose other arm 78 is provided with a projection 79. It will be noted from Figure 3 that the arms 74 and 78 of the bell cranks extend toward each other from their pivots, so that a rocking of the bell cranks in the same direction will produce movement of the member 70 and link 69 in opposite directions. As shown in Figure 7, the extent of movement of the member 70 is limited by stops 80, and the bell cranks may be adjusted with relation to the member 70 by screws and nuts as illustrated.

A fixed member 81 is provided with a guideway in which slides a member 82 pivoted to a link 83

- which is operated as hereinafter set forth. The member 82 is provided with a pin 84 on which are pivoted fingers 85 and 86 which slide in cut outs in the fixed member 81. Beneath the finger 85 is a vertically slideable pin 87 terminating at its lower end in ears 88 between which is mounted a roller 89, while beneath the finger 86 is a similar pin 90 provided at its lower end with ears 91 between which is pivoted a roller 92. Springs 93 surround the pins 87 and 90 and bear against the ears 88 and 91 and the fixed member 81 and thus tend to force the pins downwardly.
- 15 Mounted to reciprocate with the charging device 53 is a member 94 to which is secured by bolts 95 a member 96 carrying various cams. As shown in Figures 5 and 6 the rollers 89 and 92 run on a trackway 97 on the member 96 and this has at its ends elevations 98 and 99 with which cooperate the rollers 89 and 92 respectively as the charging device nears the end of its movement in either direction. As the rollers 20 run up these elevations the pins 87 and 90 are raised and this results in raising the fingers 85 and 86 alternately. As evident from Figures 3 and 5, when the fingers are raised they will pass above the projections 25 75 and 79 of the bell cranks and not actuate the same. When the parts are in the position shown in Figure 3, an operative movement of the link or connecting rod 83 will cause the finger 86 to engage the projection 30 79 of the bell crank lever and move said lever together with the member 70 and link 69. At the same time the other bell crank will be moved and the projection 75 will approach the finger 85 which however at 35 this time is elevated so that the projection passes under the finger. The rod 83 now returns to normal position and when the next movement of the member 94 takes place, the finger 85 will be dropped and the finger 86 will be elevated so that on the next movement of the link 83 the valve operating link 69 will be given movement in the opposite direction.
- The member 96 also carries a trackway 40 100 provided with a cam elevation 101 near its center. Cooperating therewith is a roller 102 on the end of a lever 103 pivoted at 104 and normally forced upward by a spring 103'. Pivoted at 106 to a frame member 50 105 which may be integral or attached to the member 81 is a link 107 the purpose of which will be hereinafter explained. This link terminates in arms 108 and 109. A spring 110 normally tends to force the arm 60 108 to the left in Figure 5, but this movement is prevented when the parts are in the position shown in this figure by the engagement of the end of the arm 108 with a notch in the lever 103. The member 96 65 also carries a trackway 111 provided with shoulders 112 at the ends thereof. When the member 94 is reciprocated until the roller 102 rides up the cam 101, the lever 103 will be rocked releasing the arm 108 of the member 107 and the spring 110 will then 70 force the arm 108 outwardly and the arm 109 will move downwardly until it engages the track 111 along which it will slide until the end of the stroke is reached when it will drop down behind the shoulder 112. This 75 will prevent the member 94 and consequently the charging device to which it is connected, from being moved in the opposite direction until the member 107 is rocked to lift the arm 109 up above the trackway 80 111, which operation will be hereinafter described.
- The pressure ram is operated by a low pressure steam cylinder 113 connected to the frame by four strain rods 114, and a high pressure steam cylinder 115 similarly connected by four strain rods 116. Each cylinder is fitted with a piston operated slide valve which in turn is controlled by an auxiliary slide valve. This structure 90 is old and well known in the art and is not here illustrated in detail, but there is shown the rod 117 which operates the auxiliary slide valve of the low pressure steam cylinder 113 and the rod 118 which operates the 95 auxiliary slide valve of the high pressure steam cylinder 115.
- The hydraulic mechanism that cooperates with these steam cylinders comprises a low pressure cylinder 119 in which works the 100 rod 120 from the steam cylinder 113. This rod is connected with a ram which slides within the cylinder which in turn is connected to the press head 121 (Figure 8) which reciprocates in the press tunnel 55. 105 A high pressure cylinder 122 is provided with a piston connected to the piston rod 123 actuated by the high pressure steam cylinder. The high and low pressure cylinders are connected by a pipe 124 connected 110 to each of the cylinders as shown in Figure 10. A surge tank 125 is connected by a pipe 126 to the pipe 124, and a valve 127 which rests loosely on a valve seat 128 controls the passage of water from the surge tank 115 to the high and low pressure hydraulic cylinders. A stem 129 is arranged to reciprocate vertically beneath the valve 128 and this stem passes through appropriate packing and terminates in ears 130 between 120 which is pivoted a roller 131 which engages the upper cam surface of a slide member 132 operated as hereinafter described. A spring 133 surrounds the stem 129 and forces the roller into contact with the cam surface. 125 The member 132 reciprocates in a guideway in a bracket member attached to the valve casing as indicated in Figure 10.
- When the parts are in the position shown in Figures 3 and 4, the slide valve in the low 130

pressure steam cylinder has just been operated to admit steam under pressure to move the piston rod 120 and the ram under low pressure.¹ The cross head 134 which moves therewith has a depression 135 in which rests a roller 136 carried by an arm fast on a rock shaft 137 mounted in appropriate bearings. An arm 138 carrying an adjustable weight 139 normally tends to rock this shaft in a direction to move the roller into the depression 135. The first movement of the cross head will cause the roller to ride up out of the depression 135 and the shaft 137 will be rocked. The shaft 137 has at its opposite end a downwardly extending arm 140 which is connected to the link 83 which operates the valve mechanism of the steam cylinder for the charging device as previously described. The initial rocking of the shaft 137 will therefore withdraw the slide member 82 and the fingers 85 and 86, thus positioning them for their next operative movement. Also carried by the shaft 137 is a downwardly extending arm 141 which carries at its lower end an adjustable set screw 142 adapted to cooperate with the cam slide 132, and when the shaft 137 is rocked the arm 141 will take substantially the position shown in Figure 4.

As the low pressure piston continues to move water is drawn in from the surge tank into the hydraulic cylinder since the valve 127 will be lifted from its seat by the flow of water outwardly from the surge tank.

The cross head 134 has mounted therein in a slot a sliding member 143 provided with a depression 144, and the cross head itself has a depression 145 nearer the end thereof. A rock shaft 146 is mounted in suitable bearings and has an arm carrying a roller 147 positioned to engage with both of the depressions 144 and 145. When the cross head has moved until the roller registers with the depression 144 the roller 147 will drop therewith into the influence of a weight 148 carried by an arm 149 on the shaft. The other end of the shaft 146 has an upstanding arm 150 connected to a link 151 which has a downwardly extending end portion 152 which embraces the valve operating rod 118 of the high pressure steam cylinder. The outer end of the link 118 is connected to a short lever 153 pivoted at 154 and having its other end provided with an adjustable set screw 155. As soon as the shaft 146 is rocked the auxiliary valve in the high pressure steam cylinder will be operated through the rod or link 118 and the high pressure piston will begin to operate. Both the high and low pressure pistons will move together, and the valve 127 will now be closed by the reversal of pressure. As soon as the low pressure cross head has moved to its limit, the slide 143 will have been moved until the

depression 144 registers with the depression 145 and the roller 147 will be seated in both depressions.

The high pressure hydraulic piston has a cross head 156 which moves therewith and this is provided with a depression 157. As the piston has about finished its stroke the roller 158 carried by an arm fast to the shaft 159 will drop into the depression 157 and the shaft 159 will be rocked by means of a weight 160 carried by an arm 161 fast to said shaft. The rocking of this shaft produces several results. An upstanding arm 162 thereon is connected by a link 163 to a short lever 164 pivoted at 165 and having its other end connected at 166 to the valve actuating rod or link 117 of the low pressure steam cylinder. Through these connections the rocking of the shaft actuates the valve gear in the low pressure cylinder and reverses the movement of the low pressure piston and the press ram. The shaft 159 also has a depending arm 167 provided with an adjustable set screw 168 in its lower end positioned to engage the cam slide 132. As the shaft 159 rocks the arm 167 will be actuated to move the slide 132 towards the left in Figure 4, causing the roller 131 to ride up the incline of the cam, raising the stem 129 and therefore opening the valve 127 to allow water to return to the surge tank during the return movement of the high and low pressure pistons.

Also as the operations just described take place a projection on the high cylinder cross head strikes the set screw 155 and rocks the lever back to the Figure 3 position, thus operating the valve rod 118 and reversing the high pressure steam devices. As the low pressure valve operating rod 117 begins its return movement a nut 170 adjustable thereon strikes the downturned end 171 of a link 172 pivoted at its other end to an arm 173 on a rock shaft 174 mounted in suitable bearings. To an upstanding arm 175 on the other end of the shaft 174 is pivoted a link 176 which is connected to the member 107 as described above. The rocking of this shaft 174 which takes place near the beginning of the reverse movement of the valve operating rod 117 will therefore pull on the rod 176, rock the member 107 about its pivot 106 and lift the arm 109 from behind the shoulder 112 thus freeing the slide 94 and charging device for movement. As soon as this arm 109 is lifted, the catch 103 will engage the other arm 108 and hold these parts in position.

Both the low and high pistons are now moving in reverse direction, and when the low piston with its cross head 134 reaches the approximate end of its movement, the roller 136 will drop into the depression 135 allowing the weight 139 to rock the shaft 137 and move the rod 83 towards the right

in Figure 3, thus actuating the valve actuating gear of the charging device which then makes its movement. At the same time the rocking of the shaft 137 through the arm 5 141 moves the slide 132 to the Figure 4 position allowing the valve 126 to close.

As the charging device now makes its movement together with the member 94, the roller 102 engaging the cam 101 will rock the lever 103 and release the arm 108 which will be forced out by the spring 110, communicating movement to the link 176 and thence to the link 172 whose lower end is in engagement with the nut 170 on the valve rod 117. The movement communicated to the link 172 will be towards the right in Figure 4 and will move the valve controlling rod 117 in a direction to again begin the cycle of operations that has just been described. 20 The rod 50 which operates the charging boxes of the fibre tank and cinder tank and the measuring device for the liquid binder, extends down as shown in Figure 3 and is operated by an appropriate moving part at 25 the desired time.

Various other details of construction may be briefly mentioned. The steam cylinder 66 of the charging device is connected to the frame by four strain rods 177. Steam may 30 be conducted to the high and low pressure steam cylinders through pipes 178 and 179, and the exhaust steam may be conducted away through a pipe 180. This exhaust steam will be sufficient to heat the various 35 steam jackets and pipes of the tanks and the press tunnel. A connection 181 may be placed in the pipe 124 for attachment of a pressure gage and safety valve if desired. Suitable packings and other common expedients in use with mechanism of this general type may be used as found necessary or 40 desirable.

It is believed that the operation of the device will be clear from the above, but it 45 may be briefly recapitulated as follows. The supply tanks will feed the material each time the charging device is operated, which will be on each actuation of the press plunger, the material passing into the mixing 50 tank where it is thoroughly agitated with the hot binder. From the mixing tank the material passes into the feeding tank and thence into the compartments 56 and 57 of the charging device. Assuming that a 55 charge is in position for pressing and that the parts are substantially in the position shown in Figure 3, the steam is then admitted to the low pressure cylinder 113 and the ram travels forward performing the low 60 pressure operation on the material. During this movement water passes from the surge tank into the low pressure hydraulic cylinder through the valve 127 which is lifted from its seat by the water itself. 65 As soon as the roller 147 comes into the

depression 144 the shaft 146 is rocked and through the link 151 communicates movement to the valve controlling rod 118 of the high pressure steam cylinder, whereupon the high pressure piston comes into operation, 70 and the valve 127 being closed, the pressure is transmitted through the water in the high and low pressure hydraulic cylinders to the press head or ram. Near the end of the pressing movement the lever 153 is rocked to 75 reverse the valve of the high pressure cylinder, and at the same time the shaft 159 is rocked as the roller 158 drops into the depression 157. The rocking of this shaft through the connections 163 and 164 moves 80 the rod 117 to reverse the valve of the low pressure steam cylinder. At the same time the rocking of the shaft 159 through the arm 167 moves the slide 132 to open the valve 126. The above mentioned movement 85 of the rod 117 through the engagement of the nut 170 with the end 171 of the link 172 rocks the shaft 174 and pulls on the link 176 to move the member 106 to release the member 94 and the charging device for movement. At this time the roller 136 drops into the cam depression 135 and the rocking of shaft 137 through the arm 141 moves the slide 132 to allow the valve 126 to close. The rocking of the shaft 137 also moves the 90 link 83 to operate the valve mechanism of the steam cylinder for the press charging device and it moves to bring the compartment 57 (Figure 7) out of register with the press tunnel and the compartment 56 containing material to be pressed into register with said tunnel. Meanwhile the compartment 57 moves into registry with the other opening 52 in the feed tank. This movement of the charging device, through the 95 cam 101 will rock the lever 103 to release the member 107 which will be forced about its pivot 106 by the spring 110, thus pulling on the rod or link 176 and the link 172 and thereby quickly moving the valve rod 117 to 100 again initiate the cycle of operations just described.

It will be noted that the charging device makes a movement in one direction only for each complete reciprocation of the press ram. 115 The completion or the return movement of the press ram initiates the movement of the charging device, and the movement of the charging device in turn initiates the next movement of the press ram. One compartment of the charging device is always being 120 filled while the material in the other is being forced out by the press ram.

Obviously many details may be varied without departing from the spirit of the invention, and it is to be understood that the invention is limited only by the scope of the appended claims.

I claim as my invention:

1. A press comprising a plurality of con-

- 5 tainers for materials, a mixing tank, means 65 for intermittently conveying measured quantities of the materials into the mixing tank, a feeding tank communicating with the mixing tank and having a plurality of feeding openings therein, and a charging device having a plurality of compartments which alternately register with corresponding openings.
- 10 2. A press comprising a plurality of containers for materials, a mixing tank, means 70 for intermittently conveying measured quantities of the materials into the mixing tank, a feeding tank communicating with the mixing tank and having a plurality of 75 feeding openings in its bottom, and a reciprocating charging device having a plurality of compartments which alternately register with corresponding openings.
- 15 3. A press comprising a plurality of containers for materials, a mixing tank, means 80 for intermittently conveying measured quantities of the materials into the mixing tank, a feed tank communicating with the mixing tank and having two feeding openings in its bottom, a press tunnel, and a reciprocating charging device having two compartments each of which alternately registers with one of said openings and with the press tunnel.
- 20 30 4. A press comprising a feeding tank having 85 feeding openings in its bottom and a central cylindrical portion, a conduit for spacing blocks passing through said cylindrical portion, and a reciprocating charging device having compartments alternately registering with said feeding openings.
- 25 5. A press comprising a feeding tank having 90 an annular form and two feeding openings in its bottom, a conduit for spacing blocks passing down through the center of the feeding tank and delivering said blocks between alternate bricks, a press tunnel, and a reciprocating charging device having two compartments, each of which alternately 95 registers with one of said openings and with the press tunnel.
- 30 6. A press comprising a feeding tank having 100 two delivery openings, a press tunnel, and a reciprocating charging device having two compartments each of which alternately registers with one of said openings and with the press tunnel.
- 35 7. A press comprising a feeding tank, a charging device receiving material therefrom and oscillating in a tunnel and a press head oscillating in a tunnel at an angle to the first tunnel.
- 40 8. A press comprising a press tunnel and a tunnel for a charging device intersecting 105 at an angle, means for oscillating a charging device in its tunnel and means for oscillating a press head in the press tunnel.
- 45 9. A press comprising a press tunnel and a tunnel for a charging device intersecting 110 at right angles, means for giving a charging device intermittent movement in one tunnel and means for giving a press head intermittent movement in the other tunnel.
- 50 10. A press comprising a press tunnel, a press head reciprocating therein, a charging device, a tunnel in which it reciprocates, the two tunnels intersecting at right angles, and means for giving the press head and charging device alternate movements in their respective tunnels.
- 55 11. A press comprising a press tunnel, a press head reciprocating therein, a charging device having two compartments, a tunnel in which it reciprocates, the two tunnels intersecting, and means for giving the press head a complete reciprocation for each movement in one direction of the charging device.
- 60 12. A press comprising a reciprocating press head, a reciprocating charging device 115 having two compartments for material to be pressed, the lines of movement of the press head and charging device intersecting, and means for giving the press head a complete reciprocation for each movement in one direction of the charging device.
- 65 13. A press comprising a charging device, means for moving the charging device, means for locking said device at the end of a movement in either direction, and means for automatically releasing said locking means.
- 70 14. A press comprising a charging device, a press head, means for moving the charging device, means for locking said device at the end of a movement in either direction, and means for releasing said locking means by the return movement of the press head.
- 75 15. A press comprising a charging device, means for moving the same, means for locking the same at the end of a movement in either direction, and means travelling with the charging device to bring the locking means into play.
- 80 16. A press comprising a charging device, means for moving the same, means for locking the same at the end of its movement, and cam operated means travelling with the charging device to bring the locking means into play.
- 85 17. A press comprising a charging device, means for moving the same, means for locking the same at the end of its movement, a 120 detent for holding the locking means out of action, and means for moving said detent to permit the locking means to become effective.
- 90 18. A press comprising a charging device, means for moving the same, means for locking the same at the end of its movement, a detent for holding the locking means out of action, and cam means travelling with said charging device to release the detent to permit the locking means to become effective.

19. A press comprising a charging device, means for moving the same, means for locking the same at the end of its movement, a spring for moving the locking means in one direction, and means for positively moving it in the other direction. 65
20. A press comprising a charging device, a press head, means for moving the charging device alternately in opposite directions, 10 means for locking it at the end of a movement in either direction, means for moving the press head, and means operated by the return movement of the press head for releasing said locking means and causing the 15 charging device moving means to operate. 70
21. A press comprising a press head, means for reciprocating the same, a charging device, means for moving the latter in one direction only for each complete reciprocation of the press head, means for locking the charging device at the end of each movement thereof, means for bringing the locking 20 means into play by movement of the charging device itself, and means for unlocking the locking means by the return movement 25 of the press head. 75
22. A press comprising a press head, means for reciprocating the same, a charging device, means for moving the latter in one direction only for each complete reciprocation of the press head, means for locking the charging device at the end of each movement, means for unlocking the locking means by the return movement of the press 30 head, and means for initiating the next movement of the charging device. 80
23. A press comprising a press head, a low pressure steam cylinder for moving the head through a portion of its stroke, a high pressure steam cylinder for moving it through the remainder of the stroke, means actuated by the movement of the head under the pressure of the low pressure cylinder for initiating the operation of the high pressure cylinder, and means operated at the end of the high pressure stroke for reversing the movement of both high and low pressure cylinders. 85
24. A press comprising a press head, a low pressure steam cylinder, a high pressure steam cylinder, a low pressure hydraulic cylinder, a high pressure hydraulic cylinder, a pipe connecting the two cylinders, a surge tank connected to said pipe, a valve controlling passage of fluid between the surge tank and hydraulic cylinders, and means for opening said valve at the end of the operative stroke of the press head. 90
25. A press comprising a press head, high and low pressure means operating thereon, means for initiating the movement by the low pressure, means for continuing the movement by the high pressure, and cam controlled means for reversing the high and low 95
- pressure means at the end of an operative stroke of the press head. 100
26. A press comprising a press head, high and low pressures hydraulic cylinders, a communication between the two, a surge tank connected to said communication, a valve for controlling the passage of fluid to and from the surge tank and hydraulic cylinders, and means for opening said valve at the termination of the operative movement of the press head. 105
27. A press comprising a press head, high and low pressure hydraulic cylinders, a communication between the two, a surge tank connected to said communication, a valve for controlling the passage of fluid to and from the surge tank and hydraulic cylinders, means for opening said valve at the termination of the operative movement of the press head, and means for closing said valve at the termination of the return movement of the press head. 110
28. A press comprising a press head, high and low pressure hydraulic cylinders, a communication between the two, a surge tank connected to said communication, a valve for controlling the passage of fluid between the surge tank and the cylinders, a movable stem underlying said valve and adapted to move the same from its seat, a slidible member adjacent the other end of the stem and means operated at the termination of the movement of the press head in each direction for operating said slidible member. 115
29. A press comprising high and low pressure steam cylinders, cross heads movable thereby, means operated by the outward movement of the cross head associated with the low pressure steam cylinder for bringing the high pressure steam cylinder into operation, and means operated by the outward movement of the other cross head for reversing the low pressure cylinder. 120
30. A press comprising high and low pressure steam cylinders, cross heads movable thereby, means operated by the outward movement of the cross head associated with the low pressure steam cylinder for bringing the high pressure steam cylinder into operation, and means operated by the outward movement of the other cross head for reversing both of said cylinders. 125
31. A press comprising a press head, a charging device, means for moving said press head, means for locking the charging device at each limit of its movement, and means operated by the movement of the locking means to operative position for initiating the movement of the press head moving means. 130

In testimony whereof, I have hereunto 125
subscribed my name.

FRANCIS E. STEVENSON.
